REVERSE LOCK SLIDER FOR SEPARABLE FASTENERS

Louis H. Morin, Bronx, N. Y., assignor to White-hall Patents Corporation, Bronx, N. Y., a corporation of New York

Application January 25, 1939, Serial No. 252,736

7 Claims. (Cl. 24—205.5)

This invention relates to separable fasteners employing stringers, and particularly to a reversible lock slider for fasteners of this kind for retaining the slider against movement on the stringers with the pull arranged in either of two positions resting upon one wall of the slider. More particularly the invention relates to a reversible lock slider of this type wherein the finger piece or pull of the slider has a sliding pivotal connection upon one wall of the slider within certain limits, and further wherein a lock pin or element is pivotally supported in connection with the pull outwardly of the pivotal end thereof to provide a more positive locking engagement of the slider, especially in what is regarded as the reverse position of the pull on the slider. The novel features of the invention will be best understood from the following description when taken together with the accompanying drawing, in which certain embodiments of the invention are disclosed, and in which the separate parts are designated by suitable reference characters in each of the views, and in which:

Fig. 1 is a plan view of a part of two stringers showing one of my improved lock sliders thereon with part of the construction broken away and in section.

Fig. 2 is a section substantially on the line 2—2 of Fig. 1.

Fig. 3 is a view similar to Fig. 2 with parts in a different position, and

Fig. 4 is a section on the line 4—4 of Fig. 1.

In Fig. 1 of the drawing 5, 5a represents portions of two stringer tapes having coupling links 6, 6a attached to the beaded edges thereof and adapted to be coupled and uncoupled by a slider 7. The slider 7 comprises the more or less conventional channeled body having top and bottom walls 8 and 9 joined by a connecting web 10 centrally of the wide end of the slider.

The top wall 8 in the construction shown is provided with an elongated central lug 11 having an elongated aperture 12 therein which opens through opposite sides of the lug and forms what might be termed a channel. At 13 I have shown a finger piece or pull having a forked end 14 for the reception of the lug 11. The inner end of the pull has a transverse pivot pin 15 fixedly coupled therewith and transversing the aperture or channel 12 so that the pull may be arranged to lie flatly upon the wide end portion of the slider as seen in full lines in Figs. 1 and 2, or upon the narrow end portion of the slider as indicated in dot and dash lines in Fig. 3. The pull may also be raised to a perpendicular or any desired angu-

lar position in the operation of moving the slider longitudinally of the stringers. The end of the pull carrying the pivot pin 15 is rounded as seen at 16 so as to permit free swinging movement of the pull as will be apparent, and the pin is movable from one end portion of the aperture 12 as seen in Fig. 2 to the other end portion thereof as is indicated by the dot and dash lines in Fig. 3.

At 17 is shown a lock pin or element which is pivotally supported as at 18 upon one side edge 10 of the pull outwardly of the pivot pin 15. The lock element 17 is supported snugly for free movement in an aperture 19 formed in the top wall 8 of the slider, so that when the pull is in the normal or resting position upon the upper surface 15 of the top wall 8 of the slider in either the full or dotted line positions thereof shown in Figs. 2 and 3, the element 17 will extend into the channel of the slider to engage at least one of the links of one of the stringers; for example, the links 6a 20 of the stringer 5a, as is clearly illustrated in Figs. 1 and 2 of the drawing. It will also appear that in the operation of grasping the pull 13 to operate the slider in either direction on the stringers, the upward or raising movement of the pull will withdraw the element 17 from the channel of the slider permitting free movement of the slider on the stringers.

It will appear from a consideration of Fig. 3 of the drawing that in the extreme upward or outward movement of the pull, the element 17 will still be retained within the aperture 19. In other words, the element 17 never becomes displaced from this aperture, regardless of the position of the pull. It will appear, however, that in the 35 automatic or manual movement of the pull from a raised to the normal resting position will cause the element 17 to be moved into the channel to engage one of the stringers.

It will appear from a consideration of Figs. 2 40 and 3 of the drawing that when the pull is in its normal or locked position, the pivot 18 of the lock element 17 is disposed in alignment with the pivot 15 of the pull. It will thus be seen that any stress or strain of the links upon the lock element 45 17 when in operative position, will in no way transfer movement to the pull tending to move the pull into an open position. While some movement may be attributed to the element 17 due to the natural clearances which are allowed in 50 the aperture 19, this movement will only amount to a swinging movement of the element on its pivot 18.

In lock sliders of conventional types, it has been the common practice to employ lock pins 55

or pawls which were integral with or rigid with the swinging member or pull or directly operable therewith and subject to accidental opening, especially when the stringers have been subjected to stress or strain tending to separate the same. With my present construction, this objectionable feature is overcome and a substantially positive lock is provided, and one which is especially adapted for use on separable fasteners of the reverse locking type; that is to say, where such devices are applied to leggings and similar garments or articles, when the normal tendency of the pull is to hang downwardly in the direction of the wide end of the slider in the manner illustrated in Figs. 1 and 2 of the drawing. In other uses of fasteners, the normal downward hanging of the pull is similar to that illustrated in dot and dash lines in Fig. 3 of the drawing.

It will of course be apparent to those skilled in the art that my invention is not restricted to any particular arrangement of the lock element upon the pull, nor to the particular contour of the pull herein disclosed.

It will appear from a consideration of Figs. 2 and 3 of the drawing that the aperture 19 in the top wall of the slider is located centrally with respect to the elongated aperture or channel 12 in the lug 11, so that the pivot pin 15 of the pull is free to move in opposite end portions of the channel 12 when the pull is swung into the two positions indicated in full lines in Fig. 1 and dotted lines in Fig. 3.

My invention is applicable to sliders and fastener stringers of the metallic as well as of the plastic types, or combinations of metallic or plastic elements may be employed. That is to say, where plastic materials are used in the construction of the slider proper and pull, the pivot pins, and if desired, the lock element, may be composed of metallic material to provide the required strength and rigidity. However, in some types of fasteners where the stringers are not subjected to excessive stress or strain, all plastic or thermoplastic materials may be employed.

It will appear from a consideration of Figs. 2 and 3 of the drawing that the lock element or pin 17 is always maintained in a position at right angles to the plane of the tape or the outer wall of the slider, or may be said to be perpendicular thereto, regardless of the position of the finger piece or pull 13. In other words, this lock element or pin has a definite inward and outward movement and is not capable of swinging movement on the slider, and thus forms a key element fitting between adjacent links of a stringer to positively lock the slider in position and to be unaffected by any stress or strain tending to move the slider longitudinally of the stringers.

Having fully described my invention, what I claim as new and desire to secure by Letters Patent, is:

1. A lock slider for separable fasteners of the class described comprising a channeled body, a lug on one wall of said body, said lug having an elongated aperture opening through opposite sides thereof, said wall of the slider at one side of the lug and centrally with respect to the aperture in said lug having an aperture opening into the channel of said body, a pull, said pull having a forked end portion, a coupling pin mounted closely adjacent the extremity of the forked end portion of the pull to extend through and operate in the elongated aperture of said lug in pivotally and slidably coupling the pull with said lug, a lock element mounted in the aperture of said wall

of the slider, said element being pivotally supported upon the pull adjacent but inwardly of said pin with respect to the extremity of the pull whereby in raising the pull with respect to said wall of the slider, the lock element is withdrawn from the channel of said slider.

2. A lock slider for separable fastener stringers of the character described, said slider comprising a channeled body having spaced side walls with a channel arranged therebetween, a pull having pivot means at one mounting end thereof, elongated bearing forming means on one wall of said slider cooperating with the mounting end of said pull and providing pivotal and limited sliding movement of said pull, said wall of the slider adjacent and intermediate the ends of said bearing forming means having an aperture opening into the channel thereof, a lock element pivotally coupled with said pull at a point slightly spaced from the means on the mounting end thereof, and said lock element being movably supported in said aperture and extending into the channel of said slider in predetermined positions of said pull.

3. A lock slider for separable fastener stringers of the character described, said slider comprising a channeled body having spaced side walls with a channel arranged therebetween, a pull having pivot means at one mounting end thereof, elongated bearing forming means on one wall of said slider cooperating with the mounting end of said pull and providing pivotal and limited sliding movement of said pull, said wall of the slider adjacent and intermediate the ends of said bearing forming means having an aperture opening into the channel thereof, a lock element pivotally coupled with said pull at a point slightly spaced from the pivot means at the mounting end thereof, said lock element registering with said aperture and being slidably movable therein in the pivotal movement of said pull between two terminal positions extending in opposite directions along said slider wall, and the length of said lock element being sufficient to extend into the channel of said slider when the pull is in either of said terminal positions.

4. A lock slider for separable fastener stringers of the character described, said slider comprising a channeled body having spaced side walls with a channel arranged therebetween, a pull having pivot means at one mounting end thereof, elongated bearing forming means on one wall of said slider cooperating with the mounting end of said pull and providing pivotal and limited sliding movement of said pull, said wall of the slider adjacent and intermediate the ends of said bearing forming means having an aperture opening into the channel thereof, a lock element pivotally-coupled with said pull at a point slightly spaced from the pivot means at the mounting end thereof, said lock element registering with said aperture and being slidably movable therein in the pivotal movement of said pull between two terminal positions extending in opposite directions along said slider wall, the length of said lock element being sufficient to extend into the channel of said slider when the pull is in either of said terminal positions, and the spaced relation of the pivot of said lock element and the pivot forming end of said pull being sufficient to provide withdrawal of said lock element from the channel of said slider in the operation of raising said pull from the terminal position thereof.

5. A lock slider for separable fastener stringers of the character described, said slider comprising

- a channeled body having spaced side walls with a channel arranged therebetween, a pull having pivot means at one mounting end thereof, elongated bearing forming means on one wall of said slider cooperating with the mounting end of said pull and providing pivotal and limited sliding movement of said pull, said wall of the slider adjacent and intermediate the ends of said bearing forming means having an aperture opening into the channel thereof, a lock element pivotally coupled with said pull at a point slightly spaced from the pivot means at the mounting end thereof, said lock element being movably supported in said aperture and extending into the channel of said slider in predetermined positions of said pull, and the engagement of said lock element with said aperture being sufficiently close to limit the movement of the pivotal coupling of said pull and lock element to a plane perpendicular to the wall of the slider and in alignment with the aperture therein.
6. The combination with a channeled slider for separable fasteners of the class described having an aperture in one wall thereof opening perpendicularly into the channel of the slider, of a lock

element fitting snugly in the aperture of the slider wall to provide movement of said element only in a direction perpendicularly to the channel of the slider, means controlling movement of the lock element in the operation of the slider, 5 said means comprising a member slidably pivoted to said slider wall, and means fixedly pivoting said member to said element.

7. In combination with a separable fastener slider having an aperture in one wall thereof opening perpendicularly into the channel of the slider, a pull pivoted at one end thereof to said wall of the slider adjacent said aperture, means movably supporting the pivot end of said pull, 10 a lock element fitting snugly in the aperture of the slider wall and fixedly pivoted to said pull adjacent the pivot end thereof, said pull having pivotal and limited sliding movement with respect to said means, and said lock element operating 15 in the aperture of the slider wall only in a direction perpendicular to the channel of the slider when moved into operative and inoperative position by said pull.
